DESIGN FOR A TOWEL BAR BRACKET

Michael S. Desser, Vineland, N. J., assignor to Kimble Glass Company, Vineland, N. J., a corporation of Illinois

Application April 5, 1939, Serial No. 84,065

Term of patent 7 years

To all whom it may concern:

Be it known that I, Michael S. Desser, a citizen of the United States of America, residing at Vineland, in the county of Cumberland and State of New Jersey, have invented a new, original, and ornamental Design for a Towel Bar Bracket, of which the following is a specification, reference being had therein to the accompanying drawing, forming a part thereof, in which

Fig. 1 is a perspective view of a towel bar bracket showing my new design;

Fig. 2 is a front elevational view of the towel bar bracket; and

Fig. 3 is a side elevational view of the towel bar bracket.

The dominant feature of the design is the arrangement of two successively raised octagonal panels within the borders of the octagonal base plate, a socket for the towel bar projecting from the smaller of the raised panels, all as shown.

I claim:

The ornamental design for a towel bar bracket, substantially as shown and described.

MICHAEL S. DESSER.
